FUSE CUT-OUT

Benjamin R. Hermann, Pittsfield, Mass., assignor
to General Electric Company, a corporation of
New York

Application February 27, 1936, Serial No. 65,994

9 Claims. (Cl. 200—114)

The present invention relates to an electric cutout, particularly of the type incorporating a fuse with mechanism capable of functioning automatically upon operation of the fuse to effect movement of the fuse from its normal position connected between stationary contact terminals to a position giving positive indication of the fuse operation.

An important object of the invention is the provision of improved operating mechanism for a cutout of the type above indicated which mechanism can be adapted to function upon operation of the fuse either to effect movement of the fuse to an indicating position without total disconnection of the fuse from the stationary contact terminals or to effect dropout of the fuse and total disconnection thereof from the stationary terminals without arcing at the terminals.

Another object of the invention is the provision of improvements in the structure of a fuse cutout which render it sturdy as well as efficient and dependable in operation under all service conditions.

Other objects and the details of the construction and operation of an illustrative example of an enclosed fuse cutout embodying the present invention will become apparent from the following description taken in conjunction with the accompanying drawing in which

Fig. 1 is a side elevation of the enclosed fuse cutout partially in section to show the relative positions of the parts thereof when the fuse is latched in its normal connected position;

Fig. 2 is a side elevation of the cutout partially cut away to show the manner in which the cutout can be adapted to give only indication upon operation of the fuse and to show the positions assumed by the parts when the fuse has moved to its indicating position;

Fig. 3 is a side elevation partially cut away to show the cutout as adapted for complete dropout and showing a step in the operation of the cutout intermediate the indicating position and the totally dropped out or disconnected position;

Fig. 4 is a partial side view of the cutout partially cut away to show the parts thereof when the fuse is in its totally dropped out position, and

Fig. 5 is a detailed perspective view of the improved supporting and operating mechanism of the cutout.

Referring to the drawing, 10 indicates a housing of porcelain or similar insulating material having an integrally formed electric creepage barrier 10' which is disposed between the stationary contacts 11 and 12 carried by the housing. These stationary contacts are adapted to have line conductors fastened thereto by means of clamping screws 11' and 12' respectively. A cover 13 is provided for the housing 10 and is mounted on the fuse 14 of

the cutout by means of the projections 15 and 16 of insulating material formed integrally with the cover and provided with openings for accommodating the fuse.

Fuse 14 is of the expulsion type and consists of a fuse tube 17 of insulating material having a contact cap 18 secured to its upper end and enclosing a fuse link, the upper end of which link is connected to contact cap 18 and the lower end of which has a conductor 20 extending out from the bottom of the fuse tube.

When the fuse 14 is in its normal connected position illustrated in Fig. 1, cover 13 is arranged to substantially completely close the opening in the side of the housing 10 to protect the parts of the cutout from weather conditions, and contact cap 18 is arranged to engage a contact finger 21 which is carried by the upper stationary contact 11. Contact finger 21 is backed up by a spring strip 22 to provide the desired contact pressure and is formed with a downwardly facing concave seat 23 which serves as a latch to prevent outward swinging of the upper end of the fuse.

Fuse 14 and the cover 13 carried thereby are supported in the housing 10 by means of a toggle mechanism, one lever arm or element 24 of which is hingedly supported on hinge pins 25 carried by projections 25' which are secured to the housing, and the other arm or element 26 of which is pivotally connected in a manner to be described to the element 24. Element 24 is pivotally connected also to an element 28 which is rigidly attached to the lower end of fuse tube 17. A tension spring 27 is connected between the two arms 24 and 26 and tends to effect collapse of the toggle mechanism. A stop 29 which is formed integrally with cover 13 cooperates with projection 16 to hold the element 28 therebetween and allow only a small amount of relative movement between the fuse tube and cover.

The details of the supporting mechanism are shown more clearly in Fig. 5 from which it will be seen that element 24 of the toggle mechanism comprises a pair of members 30 which are held in rigidly spaced apart relation by means of bracing members 31 and 32 and strap 33 and are provided with hook-shaped portions 34 for supporting the members on hinge pins 25. Though only one hinge pin is illustrated in the sectional view of the housing as shown in Fig. 1, it is to be understood that there are two hinge pins carried by two projections 25' rigidly secured to the housing in spaced apart relation. Element 26 of the toggle mechanism has pins 35 which engage openings 36 in the members 30 to provide pivotal connection between the two elements 24 and 26. Spring 27 is fastened at one end to brace member 32 carried by element 24 and at the other end to element 26 as shown at 37 and is operative as previously indicated to bias the two elements 60

of the toggle to the collapsed state illustrated in Fig. 5. The spring 27 when totally collapsed serves to prevent further collapse of the toggle mechanism. Element 26 has mounted on the 5 free end thereof a contact 38 which is arranged to engage fixed contact 12 for the electrical connection of the lower end of the fuse 14 in a manner to be described.

Element 28 is provided with an opening 40 for 10 receiving the fuse tube 17 and is adapted to be fastened rigidly upon the tube in a suitable manner as by means of a screw 41 which engages the screw threaded opening 42 in the element 28. Element 28 has also a projecting portion 43 which 15 carries pins or studs 44 and 45 which slidably engage elongated slots 46 and 47 respectively in the plates 30 to thereby effect a pivotal connection between the fuse tube 14 and the element 24 of the toggle mechanism, it being understood 20 that similar pins and slots are provided on the side of the toggle mechanism opposite to that shown in Fig. 5. Each of the slots 47 is formed to provide two communicating sections, the first of which, designated 48, has a lower edge which 25 curves upwardly and outwardly as viewed when the toggle element 24 is in the vertical position illustrated in Fig. 1, and the second of which sections, designated 49, extends downwardly at an angle to the section 48. The spacing of pins 44 30 and 45 and the arrangement of slots 46 and 47 are such that when pins 45 slide outwardly and upwardly in sections 48 of slots 47, pins 44 at the same time slide upwardly in slots 46 until pins 45 reach the beginning of sections 49 of slots 47, 35 whereupon pins 44 cease their upward travel substantially at the top of slots 46 and further outward movement of pins 45 into sections 49 produces a counter-clockwise pivoting of the fuse tube with respect to element 24 about pins 44. 40

As best shown in Fig. 1, the hinged element or lever arm 24 of the fuse supporting toggle mechanism is arranged to be latched normally in rigid engagement with the lower end of fuse tube 17 by means of the conductor 20 which is securely 45 clamped to the strap 33 by means of winged clamping screw 50 which screws into a collar 50' carried by the strap. Under these conditions the lower end of the tube 17 presses tightly against the strap. Clamping screw 50 serves also 50 to maintain in tight engagement with the conductor 20 one end of a highly conductive flexible and resilient metallic strip 51, the other end of which strip is connected to contact 38 to insure good electrical connection between that contact 55 and the lower end of the fuse to thereby minimize current flow through either the spring 27 or the elements of the toggle mechanism. The resiliency of strip 51 and the manner of bending the strip around the lower end of the toggle 60 element 26 serves to exert a force which is in opposition to but considerably less than the force exerted by spring 27 when under tension. The force of the strip is not sufficient to prevent the action of the spring to collapse the toggle mechanism but acts when the spring is in the collapsed state illustrated in Fig. 5 to exert a force sufficient to maintain the ends of the spring in secure engagement with the brace member 32 and the element 26. 65

The projections 25', which are secured to the housing 10 and carry the hinge pins 25, have integrally formed abutments 54 which are arranged to engage the lower ends of the members 30 when the fuse 14 and door 13 swing into 70 their horizontal positions illustrated in Fig. 4, 75

thus preventing further downward swinging of the fuse and door to a point at which the hook-shaped portions 34 of the members 30 might become disengaged from the hinge pins 25.

To the back of the housing 10 there is secured a mounting bar 55 for the attachment of the cutout to a suitable supporting structure not shown. For manual operation of the cutout, cover 13 is provided with a handle 56 which may be either grasped manually or engaged by a suitable form of switch stick to swing the fuse and door assembly inwardly and outwardly about the hinge pins 25.

In order to assemble the cutout for operation, cover 13 is mounted on the fuse 14 by passing the fuse tube 17 through the openings provided in the projections 15 and 16 on the back of the cover, element 28 being at the same time assembled on the fuse tube in such a manner that it is disposed intermediate the projection 16 and the stop 29. The toggle mechanism may be attached to element 28, either before or after assembly of that element on the fuse tube, by placing the toggle arm 24 so that plates 30 are disposed on either side of the projection 43 of element 28 and inserting the pins 44 and 45 through slots 46 and 47 respectively into openings provided in the projection 43. Toggle arm 24 is then latched in engagement with the lower end of the fuse tube as previously described by screwing wing screw 50 down tightly upon the end of conductor 20. So long as the fuse link connected to conductor 20 remains intact, the lower end of the fuse tube is latched firmly in engagement with the strap 33 of the toggle arm or lever 24 and pins 44 and 45 30 repose respectively in the lower ends of slots 46 and the inner ends of slots 47 as shown in Fig. 1.

Fuse 14 and its attached toggle mechanism, which is held in collapsed state by spring 27, are mounted in the housing by hooking the portions 40 34 of members 30 over the hinge pins 25 and then manually swinging the rigidly connected fuse tube 17 and toggle arm 24 upwardly as a unit about the hinge pins and forcing the contact cap 18 into engagement with contact finger 21. 45 During the upward swinging of the fuse tube, contact 38 comes into engagement with the bearing surface of lower fixed contact 12 and slides upwardly thereon to the position indicated in Fig. 1, the element 26 of the toggle being forced into 50 its extended position to place spring 27 under tension. With the spring under tension and fuse contact cap 18 in engagement with contact finger 21, the action of the spring tends to force the hingedly mounted lever arm 24 and the fuse tube 55 17 outwardly, but the combined action of seat 23 of the contact finger 21 and of resilient back- 60 ing strip 22 serves to latch the upper end of the fuse from swinging outwardly about the hinge pins while the lower end of the fuse is latched in its inward position by means of conductor 20 and clamping screw 50. The lower latch remains operative as long as the fuse link remains intact and the fuse is held thereby in its inward position connected between fixed contacts 11 and 12, 65 the connection at the upper end being through contact finger 21 to contact cap 18 and at the lower end through contact 38 and strip 51 to the conductor 20. While the fuse is in this connected position, cover 13 effectively closes the 70 open side of housing 10 to thereby protect the fuse and its supporting and operating mechanism from adverse weather conditions. If it is desired to open the cutout while the fuse link remains intact, it is necessary to grasp the handle 75

56 on cover 13, either manually or by means of a suitable switch stick, and pull outwardly with sufficient force to disengage the contact cap 18 from the seat 23 of the contact finger 21. The 5 whole fuse and toggle assembly can then be swung outwardly and downwardly until it reaches the position shown in Fig. 4 or, if desired, until it reaches a position at which the portions 34 of the members 30 can be disengaged from the hinge pins 25.

10 When the cutout is closed, that is, when fuse 14 is in its normal connected position shown in Fig. 1 and spring 27 is under tension, operation 15 of the fuse results in expulsion of conductor 20 from the lower end of fuse tube 17 and release 20 of the lower latching arrangement, whereupon 25 the toggle arm 26 is drawn downwardly by the spring to force lever arm 24 of the toggle to swing outwardly about hinge pins 25. Were it not for the 30 form of slots 47 and the engagement of pins 45 therewith, the lower end of the fuse tube would pivot about the pins 44 in slots 46 of the lever arm 24 and the fuse tube would at the same time move bodily downward under the combined action 35 of gravity and the force of the outwardly and downwardly swinging lever arm 24. However, the form of the sections 48 of slots 47 acts to compensate for the tendency of the arm 26 to move the fuse tube bodily downward and actually to 40 prevent such bodily downward movement so that contact cap 18 is not disengaged from latching seat 23. In effect the slot sections 48 serve as guideways to produce a substantially arcuate movement of the lower end of the fuse tube so that 45 the initial movement of the tube is limited to a counterclockwise pivoting of the lower end of the tube about its upper end, and slots 46 provide for lost motion between the fuse and lever arm 24 during this initial movement. An important advantage 50 of this initial pivotal movement of the fuse tube without disengagement of contact cap 18 from contact finger 21 is that the time required for pins 45 to move from the inner ends to the outer ends of the slot sections 48 affords the delay 55 necessary to permit the complete interruption of the current flow solely within the fuse tube and the blowing of conductor 20 out of the lower end of the fuse tube before the fuse drops out from between the fixed contacts. Consequently no 60 arcing occurs either between contact cap 18 and contact finger 21 or between contact 38 and contact 12, even though the fuse is moved subsequently to a position completely disengaged from the fixed contacts.

55 If there is desired only an indication of the operation of the fuse without a complete disconnection of the fuse from the stationary contacts, this may be accomplished by placing stops 58 in openings 52 in the members 30 to prevent 65 pins 45 from passing from slot sections 48 into slot sections 49. As a result of this expedient, the fuse 14 and cover 13 supported thereby are allowed to move only to the positions illustrated in Fig. 2 wherein the lower ends of the fuse 70 tube and cover protrude from the housing 10 to give positive indication of the operation of the fuse. The binding action of pins 45 against stops 75 58 and of pins 44 against the upper ends of slots 46 together with the latching action of the seat 23 prevents any further relative pivoting of the lever arm 24 and fuse tube 17 about their pivotal connection at pins 44, and the initial movement of the fuse tube is insufficient to disengage the contact cap 18 from the latching seat 23. While the fuse is in the indicating position of

Fig. 2, cover 13 still protects the parts of the cutout within the housing 10 from adverse weather conditions.

On the other hand, if complete dropout of the fuse is desired, it is necessary only to remove the pins 53 from the openings 52 so that outward swinging of toggle lever arm 24 under the influence of spring 27 can produce movement of the pins 45 into slot sections 49. Under these circumstances, pins 44 are restrained from further upward movement in slots 46 and the arrangement of the slot sections 49 is such as to permit the fuse tube 17, under the combined influence of gravity and the downward swinging of lever arm 24, to move bodily downward to the intermediate 15 position illustrated in Fig. 3 wherein contact cap 18 is shown as having dropped out of engagement with the latching seat 23.

As soon as the fuse tube 17 and cover 13 reach the positions shown in Fig. 3, they are free to 20 pivot outwardly and downwardly about pins 44 while the lever arm 24 of the toggle mechanism swings outwardly and downwardly about hinge pins 25. When the lever arm, the fuse and the door reach the positions illustrated in Fig. 4, further downward swinging of the lever arm is prevented by engagement thereof with the stops 50 while further downward swinging of the fuse and cover is prevented by the engagement of the lower 25 end of the fuse tube 17 with the strap 33 carried 30 by the lever arm. Under these conditions the fuse is completely disconnected from the fixed contacts and is in a position which gives a clear indication of the operation of the fuse and permits 35 ready removal of the fuse with its connected door 35 and toggle mechanism from the housing 10 for servicing.

When the cutout is in the complete dropped out state illustrated in Fig. 4, the elements 24 and 26 of the toggle mechanism are prevented from further collapse by the combined action of the spring 27 in its compressed state and the resilient flexible strip 51 and hence the two elements are maintained sufficiently spread apart so that the ends 40 of the spring cannot become disengaged from 45 the brace member 32 and the element 26, respectively.

The structure of lever arm 24 comprising two members 30 rigidly braced in spaced apart substantially parallel relation and the hinged mounting of these two members on rigidly supported spaced apart hinge pins 25, and also the connection of element 26 to element 24 at two opposite points provides a sturdiness and rigidity 50 which is highly desirable in cutouts designed for 55 heavy duty service and subjected to severe shocks in operation. These and other features of my improved construction described hereinbefore provide a sturdy device which is capable of functioning dependably and efficiently and the parts 60 of which are not likely to become impaired or deranged during normal service.

What I claim as new and desire to secure by Letters Patent of the United States, is:

1. In an electric cutout, the combination of 65 spaced upper and lower contacts, a fuse, a lever hingedly mounted at one end and connected for supporting the fuse, means for holding the lever in a substantially upright position and in rigid 70 relation to the fuse, said holding means being 75 releasable by operation of the fuse, means for connecting the fuse between the contacts and including a latch for preventing swinging of the upper end of the fuse out of engagement with the upper contact, means operative upon release 75

of said holding means for actuating the lever outwardly to move the lower end of the fuse outwardly, and means carried by the lever for restraining the lower end of the fuse to move in a substantially arcuate path about the upper end of the fuse and for preventing movement of the fuse to disengage said upper end thereof from the upper contact.

5. In an electric cutout, the combination of upper and lower spaced contacts, a fuse, means for connecting the fuse between the contacts including a latch for holding the upper end of the fuse from swinging outwardly from engagement with the upper contact, and lever mechanism supporting said fuse and including means effective upon operation of the fuse for causing an initial outward swinging movement of the lower end of the fuse about the upper end thereof without disengagement of said upper end from the upper contact, said lever mechanism including also means operative subsequently to said initial movement for effecting bodily movement of the fuse to disengage the upper end thereof from the upper contact.
10. 6. In an electric cutout, the combination of spaced contacts, a fuse normally connected between the contacts, means effective upon operation of the fuse for actuating one end of the fuse towards its disconnected position, means for restraining the other end of the fuse in its connected position, and supporting means for the fuse having curved guideways slidably connected with the fuse and operative to limit the initial movement of said one end of the fuse to a substantially pivotal movement about said other end of the fuse.

15. 7. In an electric cutout the combination of spaced contacts, a fuse, means for connecting the fuse between the contacts, means tending to force the fuse out of its connected position, means for latching the fuse in its connected position against the action of said forcing means and arranged to be released by operation of the fuse, a stud member secured to and projecting outwardly from the fuse, a supporting device for the fuse having an elongated slot arranged to receive said stud member to guide the fuse in its outward movement, and stop means removably secured to said supporting device at a predetermined point for engaging said stud member to limit the travel thereof in said slot.

20. 8. In an electric cutout, the combination of a mounting base, spaced contacts carried by the base, a fuse, means for connecting the fuse between the contacts, means for movably mounting the fuse on the base comprising a pair of elements attached respectively to the base and to the fuse and pivotally and slidably connected for relative movement with respect to each other, means for latching one end of the fuse in its connected position, means for latching the other end of the fuse in its connected position and released by operation of the fuse, and means operative upon release of said last mentioned latching means for effecting outward movement of said other end of the fuse toward disconnecting position, said two mounting elements having means cooperative to restrict the initial movement of said other end of the fuse to substantially pivotal movement about said one end of the fuse and cooperative also to provide continuous support for the fuse.

25. 9. In an electric cutout, the combination of spaced contacts, a fuse normally connected between the contacts, latching means normally

holding one end of the fuse in its connected position, means for movably supporting the fuse including a supporting element having elongated slots and a second element rigidly attached to the fuse and having means slidable in said slots, and means released by operation of the fuse for effecting movement of the fuse, said slots being formed to continuously engage said slidable means to provide continuous support for the fuse and having portions formed to guide the slidable means initially in a manner to produce pivotal movement of the fuse substantially about said one end and other portions formed at such angles to said first portion as to guide said slidable means subsequently in a manner to produce bodily movement of the fuse to disengage said one end thereof from said latching means.

10. 7. In an electric cutout, the combination of spaced contacts, a fuse normally connected between the contacts, a hingedly mounted lever arm pivotally connected to the fuse for movably supporting the same, means normally operative for holding the lever arm in rigid relation to the fuse with the fuse in connected position, said holding means being releasable by operation of the fuse, means operative upon release of said holding means for effecting movement of the fuse, means providing for lost motion between the lever arm and the fuse, and guide means carried by the lever arm and operatively connected to the fuse for restraining one end of the fuse to pivot substantially about the other end thereof upon release of said holding means.

15. 8. The combination of spaced contacts, a fuse, a hingedly mounted lever arm pivotally connected to the fuse for supporting the same, means normally operative for holding the lever arm in fixed relation with the fuse and arranged to be released by operation of the fuse, means for connecting the fuse between the contacts including a latch for preventing one end of the fuse from swinging out of engagement with one of the contacts, and means operative upon release of said holding means for exerting force tending to move the fuse towards its disconnecting position, said lever arm having an elongated slot providing for lost motion between the fuse and lever arm and having a second elongated slot operatively connected for controlling the movement of the fuse, said second slot having a first portion formed to produce an initial substantially arcuate movement of the other end of the fuse about said one end and to prevent bodily movement of the fuse to disengage said one end from said one contact during such initial movement and having a second portion formed to provide for a subsequent bodily movement of the fuse to a totally disconnected position.

20. 9. In an electric cutout the combination with spaced contacts and a fuse normally connected between the contacts, of means for rigidly supporting the fuse including a lever arm having two portions extending in substantially parallel rigidly spaced apart relation and formed for the hinged mounting of the lever arm, fixedly mounted hinge supporting means arranged for the connection of said two portions of the lever arm thereto at spaced apart points, said lever arm having also two substantially parallel rigidly braced apart portions arranged to extend on opposite sides of the fuse, and an element secured to the fuse and having pivot pins engaging openings provided in the last mentioned two portions of the lever arm.
